CARD GAME ACCESSORY

Frank Sanderson, Kingman, Ariz.

Application December 20, 1950, Serial No. 13,505

Term of patent 14 years

(Cl. D34—5)

To all whom it may concern:

Be it known that I, Frank Sanderson, a citizen of the United States, residing at Kingman, in the county of Mohave and State of Arizona, have invented a new, original, and ornamental Design for a Card Game Accessory, of which the following is a specification, reference being had to the accompanying drawing, forming a part hereof.

Fig. 2 is a vertical sectional view, on the plane indicated by the line 2—2 in Fig. 1; and

Fig. 3 is a cross sectional view, on the plane indicated by the line 3—3 in Fig. 1.

The dotted lines in the drawing are for illustrative purposes only.

I claim:
The ornamental design for a card game accessory, as shown and described.

FRANK SANDERSON.
